US0D1023122S

(12) **United States Design Patent** (10) **Patent No.:** **US D1,023,122 S**
(45) **Date of Patent:** **** Apr. 16, 2024**

(54) **GLASSES FRAMES**

(71) Applicant: **PAIR Eyewear, Inc.**, New York, NY (US)

(72) Inventors: **Nathan Kondamuri**, Brooklyn, NY (US); **Sophia Edelstein**, Brooklyn, NY (US); **Lee Zaro**, Rancho Palos Verdes, CA (US)

(73) Assignee: **PAIR EYEWEAR, INC.**, New York, NY (US)

(**) Term: **15 Years**

(21) Appl. No.: **29/914,183**

(22) Filed: **Oct. 13, 2023**

Related U.S. Application Data

(62) Division of application No. 29/775,184, filed on Mar. 22, 2021.

(51) **LOC (14) Cl.** **16-06**

(52) **U.S. Cl.**

USPC **D16/329**

(58) **Field of Classification Search**

USPC D16/300, 302, 304, 306, 311, 312, 313, D16/321, 325, 326, 327, 328, 329; D29/104, 105, 106, 108, 109, 110; D24/110.1, 110.2, 110.3; D21/659, 660; D11/201

CLAIM

The ornamental design for glasses frames, as shown and described.

DESCRIPTION

FIG. 1 is a front perspective view of glasses frames;

FIG. 2 is a front view of the glasses frames;

FIG. 3 is a rear view of the glasses frames;

FIG. 4 is a right side view of the glasses frames;

FIG. 5 is a left side view of the glasses frames;

FIG. 6 is a top view of the glasses frames; and,

FIG. 7 is a bottom view of the glasses frames.

1 Claim, 4 Drawing Sheets
